UNITED STATES PATENT OFFICE.

GEORGE SERGEEFF, OF PHILADELPHIA, PENNSYLVANIA.

CARTRIDGE-HOLDER.

1,137,548.

Specification of Letters Patent. Patented Apr. 27, 1915.

Application filed September 2, 1914. Serial No. 859,797.

To all whom it may concern:

Be it known that I, GEORGE SERGEEFF, a citizen of the United States, and a resident of Philadelphia, county of Philadelphia, 5 and State of Pennsylvania, have invented a new and Improved Cartridge-Holder, of which the following is a full, clear, and exact description.

The prime object of my invention is to 10 provide a cartridge holder whereby to load simultaneously all the chambers of a magazine fire-arm.

In carrying out the invention use is made of a plurality of individual elements, each 15 being provided with means to detachably hold a cartridge. The elements are connected to move in their common plane into a form to dispose the cartridges in a circular series parallel to each other, corresponding 20 with the chambers of the magazine, or to a position with the elements in a straight line relation with one another. In the latter position the device with the cartridges thereon is more conveniently carried and more compactly packed in quantities for shipping.

I provide a resilient means which may be in the form of an elongated spring so arranged as to normally tend to dispose the elements with the cartridges in circular 30 form. To hold the elements in a straight line against the tension of the spring, latch elements are provided which are manually releasable to permit the spring to assume the curved form and dispose the cartridges circularly, corresponding with the chambers of 35 the magazine to be loaded.

The invention will be particularly explained in the specific description following:

Figure 1 is a back view with parts in section showing the several individual cartridge holders disposed in a straight line; Fig. 2 is an inverted sectional plan view, the section being indicated by the numerals 2 in Fig. 1; Fig. 3 is a front view; Fig. 4 is a 40 rear view with the elements disposed in a circular series; Fig. 5 is a side elevation on a reduced scale with the elements disposed as in Fig. 4, the view including a portion of a magazine fire-arm and indicating cartridges on the holder; and Figs. 6, 7 and 8 are respectively transverse vertical sections on the lines 6-6, 7-7, and 8-8 in Fig. 1.

It is to be understood that the form of the invention as illustrated is given so as to 50 illustrate one practical embodiment of the

invention and the latter is not confined to the specific construction shown.

In practice the device will be composed of a plurality of individual elements corresponding in number with the number of 60 chambers in the fire-arms to be loaded; the illustration shows five elements, comprising outermost elements 10, a central element 10^a and intermediate elements 10^b. On the opposed edges the several elements are formed 65 with ears 11 to receive hinge pins or pivot pins 12, so the several elements, preferably formed of sheet metal, may turn on their pivots in their common plane. One ear 13 of a mating pair is depressed so that the elements 10, 10^a, 10^b lie in the same plane.

Arranged in connection with the several elements is spring 13, which normally tends to assume a curved form as illustrated in Fig. 4, whereby to dispose the elements in 70 a circular series. Opposed side edges are formed as indicated at 14 on respective elements, and these are radial to the center of the curved spring 13, and radial to the 75 circle of the series of elements. To give a broad contact surface and prevent the elements from passing each other, the radial portions 14 are flanged as shown. On each of the elements on the face thereof I provide means to detachably retain a cartridge in a way that several cartridges will 80 be displaced by a relative turning movement of the circular series of elements on their common axis, the said cartridge containing means being separated to present intervening 85 spaces to permit the side entrance and escape of the cartridges. In the example shown the cartridge retaining means comprises an upper curved hooked flange 15 and a lower hooked flange 16. These flanges are 90 curved transversely and are more or less resilient, so that the flange *a* of the cartridge A may be slipped in laterally. The cartridges will thus be held perpendicular to the faces of the several elements and parallel with one another.

The spring 13 is secured to the central element 10^a and has slidable engagement with the outermost elements 10. Said outermost elements have lugs 17 bent outwardly from the sheet material forming the elements and the ends of the spring 13 have sliding movement in said lugs. To fasten the spring at the center a plate 19 is employed in the illustrated example and is disposed at the back 100

105

110

of the element 10^a. The upper and lower ends of the plate 19 are turned forwardly at 20 and passed through corresponding holes in the plate 10^a, said members 20 being upset 5 to rigidly hold the plate in position. Ears 18 are bent upwardly from the plate 19 and turned over the spring 13 to tightly hold the same in position. By the described arrangement the spring 13 normally tends to 10 assume its curved form, so as to carry the outermost elements 10 toward each other, the several elements swinging on their pivots 12.

In order to maintain the elements in a straight line as in Fig. 1, I provide a latch 15 means which consists of elongated spring wires 21, in the form illustrated. One spring wire 21 is secured at its outer end to each of the outermost elements 10, the connection being effected by producing a lateral bend 22 at the end of said spring and passing the latter beneath a keeper 23 on each element 10. Said keeper is produced by forming parallel slits in the material element 10 and pressing the intervening material outwardly, as will clearly appear from Figs. 1, 2 and 6. The spring latches 21 pass also through lugs 24, which are turned about the said spring, as best seen in Fig. 7, so as to permit the latches to have sliding movement in the said lugs. The spring latches 21 are of a length, so that when the elements forming the holder are in a straight line, as in Fig. 1 the free ends of said latches will be adjacent to each other. The free end of 30 each spring latch is bent downwardly as at 25, and said bent end is given approximately a V-shape, so as to present an inclined back surface. The bent ends are adapted to be received in a vertical opening 26^a formed in 35 the top 26 of the plate 19. The said top 26 is formed also at each side with inclines 27 leading to the opening 26^a. The elements 26—27, therefore, of the plate 19 thus constitute a catch to engage the bent ends 25 of the spring latches 21, and as the elements 10, 10^a and 10^b are sprung into a straight line against the tension of the spring 13, the bent ends 25 of the spring latches will ride up the inclines 27 and will then spring downwardly 50 into the opening 26^a, thereby maintaining the several individual holders 10, 10^a, and 10^b in a straight line, approximately.

I provide means adjacent to the described catch to release the spring latches 25; preferably I combine the latch releasing device with a handle element for carrying and manipulating the cartridge holder. The specific arrangement of the release device and handle is as follows: The handle 28 is 55 formed integrally with the central element 10^a, and extends rearwardly therefrom, as best seen in Fig. 8, and is return bent, the underside 29 extending forwardly, adjacent to the plate 19 and being free. Said member 60 29 is resilient and its free end lies be-

neath the opening 26^a and sufficiently below the same to permit the entrance of the hooked ends 25 of the latches 21. The arrangement is such that the handle 28 may be grasped, so that the two members are 70 between the thumb and the first finger of the user. The resilient lower member 29 may thus be forced upwardly toward the member 28 and thereby engage the hooked ends 25 of the latches, and raise the free 75 ends of such latches until the inclined surfaces at the back of the said hooked ends are free to ride over the upper ends of the inclines 27, as the curved spring 13 assumes its curved form and moves the pivoted elements bearing the cartridges into the circular form illustrated in Fig. 24.

The cartridges disposed in circular form and held by the holder are presented, as indicated in Fig. 5, to the several chambers of 85 the magazine *b* of the fire-arm *B*, and the cartridges are entered in said chambers to nearly the full extent. A turning of the cartridge holder about its axis will now cause the retaining flanges 15—16 to slip 90 from the flanges *a* of the cartridges *A*, thereby disengaging the latter. In order to insure a separation of the cartridges from the holder and cause the cartridges to be pressed home into the chambers of the magazine, I 95 provide plate springs 30 or equivalent means to give a forward impulse to the cartridges and exert a relative rearward pressure on the holder. These plate springs 30 may be secured by pressing up a portion 31 from 100 each element 10, 10^a and 10^b and clamping one end of the spring beneath said part 31. In order that the springs 30 may lie flush with the seat surface provided on the face of each individual holding element, said 105 element is depressed as at 32 sufficiently to receive the spring. It will thus be seen that upon the release of a cartridge from its retaining flanges 15—16, the spring will act to exert a forward push on the cartridge. 110

Having thus described my invention, I claim as new, and desire to secure by Letters Patent:

1. A cartridge holder having a plurality of movably connected elements provided 115 with cartridge-retaining means, and means on said holder to dispose the elements with the cartridge-retaining means in a circular series corresponding with the circular series of chambers in the magazine of a firearm. 120

2. A cartridge holder comprising a plurality of elements connected for relative movement in their common plane, individual cartridge-retaining means on said elements, and resilient means on said holder 125 tending to dispose the elements with the cartridge-retaining means in a circular series corresponding with the circular series of chambers in the magazine of a firearm.

3. A cartridge holder having a plurality 130

of relatively movable elements provided with cartridge-retaining means, means on the holder tending to dispose said elements in a circular series, and means on the holder 5 to lock said elements approximately in a straight line.

4. A cartridge holder comprising a series 10 of connected members provided with individual cartridge-retaining means, said elements being movable to a position approximately in a straight line, or into a position with the cartridge-retaining means disposed in circular series, latch means to maintain the elements in the first-mentioned position, 15 and means to retain said elements in the second mentioned position.

5. A cartridge holder comprising a plurality of relatively movable connected elements, said elements being movable into positions approximately in a straight line, or 20 into positions to form an annular series, and resilient means tending to dispose said elements in one of the said positions, and being yieldable to permit the disposal of said 25 members into the other of said positions.

6. A cartridge holder comprising a plurality of relatively movable elements each 30 provided with cartridge-retaining means, and an elongated spring ranging across said elements and normally tending to assume a curved form whereby the elements will form an annular series.

7. A cartridge holder, comprising a plurality of relatively movable elements each 35 provided with cartridge-retaining means, an elongated spring ranging across said elements and normally tending to assume a curved form whereby the elements will form an annular series, said elements being movable into approximately a straight line 40 against the tension of the spring, and means to hold the elements in the said straight line.

8. A cartridge holder comprising a plurality of elements pivotally connected edge 45 to edge with each other, to have relative movement in their common plane, each element, being provided with means to detachably retain a cartridge, and spring means 50 tending to dispose said members with their cartridge-retaining means in a circle, said elements presenting contacting side edges radial to the center of said circle, the said 55 elements being movable against the tension of the said spring means to positions approximately in a straight line.

9. In a cartridge holder, a plurality of elements movably connected to have movement 60 relative to one another in their common plane, cartridge-retaining means on said elements, resilient means on said elements tending 65 to dispose the same with the cartridge-retaining means in a curved series, latch means to hold the elements approximately in a straight line, and a releasing device for 70 said latch means.

10. In a cartridge holder, a plurality of connected elements movable relatively to one another in their common plane, cartridge-retaining means on said elements, resilient means associated with said elements 70 and tending to dispose the same with the cartridge-retaining means in a curved series, spring latches carried by certain of said elements, a co-acting catch on another of said elements in position to engage the latches 75 when the elements are approximately in a straight line, and a releasing device movable into a position to disengage the latch means and permit the mentioned resilient means to 80 function.

11. In a cartridge holder, a series of separate elements having on a face thereof means to retain cartridges, and movable in their common plane, means to dispose the elements with the cartridge-retaining means in curved 85 form, latch means to hold the elements approximately in a straight line, and a handle member at the back of the holder, the handle comprising a member movable to release 90 the latch means.

12. In a cartridge holder, a series of separate elements having on the face thereof means to detachably retain cartridges, and being movable in their common plane into a straight line, spring means normally tending 95 to dispose the elements with the cartridge retaining means in a circular line, and a handle member at the back of the holder.

13. A cartridge holder, comprising a plurality of elements relatively movable in their 100 common plane, spaced members on said elements to engage or disengage a cartridge by a relative lateral movement, and means tending to dispose the said elements with their cartridge-retaining means in a circular 105 series.

14. In a cartridge holder, a series of generally flat elements movably connected edge to edge with one another to have movement 110 relatively to one another in their common plane, cartridge-retaining means on said elements on a face thereof, and resilient means normally tending to dispose the elements with their cartridge-retaining means in a circular series, said elements having lateral 115 flanges at side edge portions thereof, and said edge portions being radial to the center of the circular series of cartridge-retaining means.

15. A cartridge holder comprising a plurality of elements movable relatively to one another in their common plane, and each presenting a front face, means to hold a cartridge on the face of each element, an elongated spring secured to an inner element 120 and extending to the end elements, the said spring being normally curved to dispose the elements in a circular series, said elements being movable to positions approximately 125 in a straight line, latches secured to the 130

outermost elements and extending toward the said inner element, and a catch on the said inner element adapted to be engaged by the said latches when the elements are in a straight line.

16. A cartridge holder comprising a plurality of elements movable relatively to one another in their common plane, cartridge-retaining means on each of said elements 10 at the front, a normally curved spring tending to dispose said elements with the cartridge-retaining means in a circular series, said spring being slidably connected with the outermost elements and secured to an inner element, spring latches secured to the outermost elements and slidably connected 15

with elements inward from the outermost elements, a catch on an element inward from those with which the latches have sliding connection, said catch being adapted to be 20 engaged by the inner ends of the latches when the elements are approximately in a straight line, and a movable device adjacent to the catch for releasing the latches.

In testimony whereof I have signed my 25 name to this specification in the presence of two subscribing witnesses.

GEORGE SERGEEFF.
